LOAD TRANSFER JOINT APPARATUS

Albert C. Fischer, Chicago, Ill.

Application February 20, 1940, Serial No. 319,902

9 Claims. (Cl. 94—18)

This invention has to do with apparatus for interconnecting paving slabs or the like at their adjacent edges, and relates more particularly to such an apparatus comprising a foundation or supporting member disposed mutually beneath adjacent edge sections of slabs and carrying relatively movable lugs for projecting upwardly respectively into said edge sections to cooperate with the supporting member in holding the slab edges in horizontal alignment while permitting their relative horizontal adjustment pursuant to expansion and contraction of the slabs when they are subjected to temperature changes.

The invention further contemplates and has as its objects, a joint structure that substantially eliminates any leakage of moisture through it to the road bed; a joint with means for supporting a joint board upright while the material for forming the slabs is poured; improved reinforcing studs for projecting upwardly from the joint supporting member into the slabs; a novel mounting for such of said studs as are for projecting into one of the slabs and which mounting allows movement of those studs with their slab relatively to the joint supporting member and the adjacent slab; new crushable means for excluding foreign material from spaces within the joint supporting member and that accommodate the relative movement of said studs; a new crushable strip along an edge of the joint supporting member to provide for expansive movement of the slabs; and a joint structure which may be economically fabricated at a distant point and conveniently transported to its place of use.

Additional objects and advantages of the present invention will become apparent when reading the following description with reference to the annexed sheet of drawings comprising a part of this specification, and wherein:

Fig. 1 is a fragmentary view, taken in angular perspective, of a road bed and a joint structure thereon embodying a preferred form of the invention;

Fig. 2 is a longitudinal vertical sectional view taken upon the line 2—2 of Fig. 1;

Fig. 3 is a transverse vertical sectional view taken through a load joint structure embodying the form of joint foundation member illustrated in Fig. 1, but having lugs of different form associated therewith; and

Fig. 4 is a view similar to Fig. 3, and illustrating a different type of compressible edge strip for the base or foundation member.

With reference now to Fig. 1, it is to be understood that the form of apparatus there shown in-

cludes a longitudinal plate-like foundation member 10, which, in this instance, is assumed to lie flatly upon and transversely of a prepared road bed of which the surface is shown at 11. Said 5 foundation member 10, which is preferably made of a wide metal strip, has a plurality of joint board supporting or abutment members 12 arranged in pairs selectively spaced along a central longitudinal section thereof. The foundation member 10 will be so arranged across the road bed that the abutment members 12 will be placed for receiving and holding a joint board 13 (shown in dotted outline) at a position where a joint is to be made between paving slabs as 14 and 15, also shown in dotted outline. Said abutment members 12 have their lower ends anchored within recesses 16 in the member 10, although any other suitable means, such as welding, may be used for maintaining these parts assembled with 10 said member.

A plurality of headed studs 17 are threaded into holes 18 which are distributed at selected intervals along a longitudinal portion of the member 10 adjacent to its right edge. Any standard 25 means may be employed for attaching the shanks of said lugs 17 to the member 10. Elongated openings 19, extending transversely of the member 10, are distributed longitudinally of said member 10, at intervals corresponding to the spacing of 30 the holes 18. The shanks of upwardly extending lugs 20 are disposed in these openings for movement transversely of the member 10 when the apparatus is placed in operation. Said lugs 20 are originally held in their respective openings 19, 35 in a central position as shown, by means of compressible or crushable bodies 21 which may be made of rubber or an asphaltic compound. The lower ends of the studs 20 are threaded and turned into threaded apertures 22 in a connecting bar 23 disposed lengthwise of and beneath the member 10. A strip 24 of rubber, cork, asphalt or other compressible material and substantially equal in thickness with the plate 10 has an edge thereof adhesively or otherwise secured 40 to an edge of said foundation member.

After the apparatus has been placed upon the road bed in the manner above described, slab forming material as soft concrete will be poured upon opposite sides of the joint board 13 in 45 any conventional manner and permitted to harden for forming the slabs 14 and 15. The slab 14 will mold itself about the strip 24 and over the upper surface of the member 10 to the left of the joint board 13. The upwardly projecting parts of the lugs 20 will be embedded 50 55

in the slab 14. Likewise, the upwardly projecting parts of the lugs 17 will be embedded in the slab 15. The bodies 21 of compressible material, since they fill the openings 19 about the shanks of the studs 20, will prevent the concrete from entering into said openings 21. A coating of dusting material, or a layer of any kind of material unadapted to be assimilated by or affected by the soft concrete to adhere to the member 10 may be spread upon that part of the upper surface of said member beneath the slab 14.

In the operation of the apparatus, assuming the slabs 14 and 15 to be expanding under the influence of heat, said slabs 14 and 15 will advance their opposed edges at the opposite sides of the joint board 13 toward one another. In doing so, the slab 15 because of the lugs 17 being embedded therein, will advance said lugs and the plate 10 with it. However, the slab 14 will simply slide upon the member 10 compressing the strip 24 and the joint board 13 and advancing the lugs 20 therewith incident to compressing or crushing the bodies 21.

Upon contraction of the slabs 14 and 15 when cooled, the slab 14 will again slide upon the plate 10 but in the opposite direction while withdrawing the studs 20 and compressing the opposite ends of the compressible members 21. If the material from which strip 24 is made is "recoverable" it will then expand to follow the retractive movement of the slab 14.

The studs as 17 and 20 projecting upwardly from the member 10 will be long enough for extending into their respective slabs only a sufficient distance to acquire a firm anchorage therein. The most of any unequalized downward forces exerted by the slabs 14 and 15 due to vehicle traffic will be reacted to by the plate member 10. Consequently the studs 17 and 20 are sufficiently effective when projecting into the slabs but a short distance, and since they are comparatively remote from the edges of the slabs and are required to exert but comparatively small force components the slabs are spared of severe critical stresses.

A further advantage of the structure illustrated in Figs. 1 and 2 is the inherent sealing character of its parts to prevent the seepage of water downwardly through the joint to the road bed. There will be an absolute seal between the slab 15 and the upper face of the plate 10 against which it is cast, and there will be a very substantial seal between the upper face of the member 10 and the underside of the slab 14, this seal being augmented by the pressure of the slab 14 upon the member 10 and by the great breadth of the contacting area between these parts.

That embodiment of the invention shown in Fig. 3 differs from that shown in Figs. 1 and 2 only by the form of lugs there employed. Those parts shown in Fig. 3 which are the same as in Figs. 1 and 2 are identified by the same respective reference character with the letter "a" added.

The fixed lugs in Fig. 3 are designated 30 and have short vertical legs 31 of which the lower ends are in threaded relation with the threaded openings 18a. Each of these lugs 30 has a horizontal leg 32 turned toward the adjacent edge of the plate 10a and away from the edge of the slab 15a presented to the joint board 13a. Said legs 32 serve the purpose of the heads upon the studs 17 described above, but by projecting more distantly into the slab as 15a they obtain a firmer

engagement with it. Likewise, the lugs 33 which are substituted for the lugs 20 have vertical legs 34 extending through the openings 19a and bodies 21a into threaded engagement with the bar 23a, and present horizontal legs 35 deeply into the slab 14a. The horizontal legs 32 and 35 upon the lugs 30 and 33, since they engage a greater section of slab, offer greater resistance to tilting of the plate 10a relatively to slabs 15a and 14b and thus make a very rigid joint structure which offers much resistance to said slabs being forced out of horizontal alignment.

The structure shown in Fig. 4 is the same as that in Figs. 1 and 2 with the exception of the compressible member 40 at the edge of the foundation member 10b, and, therefore, the parts shown in Fig. 4 are identified by the same reference characters as those in Figs. 1 and 2 with the letter "b" added. The compressible strip 40 of this structure is L-shape in transverse section, it having a comparatively short thick leg or flange 41 which is co-extensive with the thickness of the plate 10b. A horizontal leg or flange 42 of the member 40 covers the entire upper surface of the plate 10b to the left of the joint board 13b. The abutting portions of the leg 41 and the edge of the plate 10b may be adhesively joined for holding these parts in assembly. Apertures 43 are provided in the horizontal leg 42 for receiving the shanks of the lugs 20b, and since the flange or leg 42 covers the elongated openings 19b there is no need for compressible bodies as 21 shown in Fig. 1. In this form of apparatus the flange 42 serves as a divider between the slab 14b and the member 10b so there is freedom of movement between said slab and said member when the slabs 14b and 15b expand or contract.

My improved joint apparatus may obviously take other forms without departing from the spirit of the inventor. Moreover, it will be understood the apparatus is applicable in any art where slabs are to be joined and held in alignment, and it is intended the appended claims shall be so construed.

I claim:

1. Load transfer apparatus comprising a joint foundation member, slab anchorage means projecting upwardly from a section adjacent to one edge of said member, cut-away sections adjacent to the opposite edge of said member, additional upwardly extending slab anchorage means disposed in said cut-away sections for movement transversely of said edges, and means for initially holding said additional anchorage means in predetermined relation with said cut-away sections and for excluding foreign material from said cut-away sections, comprising crushable means disposed between such additional anchorage means and said foundation member at said cut-away sections.

2. Load transfer apparatus comprising a longitudinal joint foundation member, slab anchorage means projecting upwardly from a section adjacent to one longitudinal edge of said member, a plurality of cut-away sections spaced lengthwise of a portion of said member adjacent to and parallel with the opposite longitudinal edge of said member, slab anchorage lugs projecting upwardly from said member and respectively disposed in said cut-away sections for movement transversely of said edges, crushable means in said cut-away sections about said lugs for yieldably maintaining said lugs in predetermined positions, and rigid means interconnecting said lugs

whereby force transmitted to one or more of the lugs transversely of said longitudinal foundation member will be opposed by the crushable means about adjacent of said lugs.

3. Load transfer apparatus comprising a longitudinal joint foundation member, slab anchorage means projecting upwardly from a section adjacent to one longitudinal edge of said member, a plurality of cut-away sections spaced along a portion of said member adjacent to and parallel with the opposite longitudinal edge of said member, upwardly projecting slab anchorage lugs respectively disposed in said cut-away sections for movement transversely of said edges, crushable means in said cut-away sections about said lugs for yieldably maintaining said lugs in predetermined positions, and a bar-like member extending lengthwise beneath the foundation member and rigidly interconnected with said lugs whereby force transmitted to one or more of the lugs transversely of the foundation member will be opposed by the crushable means about adjacent of said lugs.

4. Load transfer apparatus comprising a longitudinal joint foundation member, slab anchorage means projecting upwardly from a section adjacent to one longitudinal edge of said member, a plurality of cut-away sections spaced within a portion of said member adjacent to and parallel with the opposite longitudinal edge of said member, upwardly projecting slab anchorage lugs respectively disposed in said cut-away sections for movement transversely of said edges, and means for initially holding said lugs in predetermined relation with said cut-away sections and for excluding foreign material from said cut-away sections comprising crushable means disposed in said sections about said lugs.

5. Load transfer apparatus comprising a longitudinal joint foundation member, joint board holding means distributed in spaced relation along a central longitudinal section of said member, slab anchorage means projecting upwardly from a longitudinal section of said member upon one side of said central section, a plurality of cut-away sections distributed in spaced relation along a longitudinal section upon the other side of said central longitudinal section, upwardly projecting slab anchorage lugs disposed respectively in said cut-away sections for movement transversely of said member, and means for initially holding said lugs in predetermined relation with said sections and for excluding foreign material from said sections, comprising crushable means in said sections about said lugs.

6. Load transfer apparatus comprising a longitudinal joint foundation member, joint board

holding means distributed in spaced relation along a central longitudinal section of said member, slab anchorage means projecting upwardly from a longitudinal section of said member upon one side of said central section, a plurality of cut-away sections distributed in spaced relation along a longitudinal section upon the other side of said central longitudinal section, slab anchorage lugs disposed respectively in said cut-away sections for movement transversely of said member, crushable means about said lugs for excluding foreign material from said cut-away sections, and a bar-like member extending lengthwise beneath the foundation member and rigidly interconnected with said lugs whereby force transmitted to one or more of the lugs transversely of the foundation member will be opposed by the crushable means about adjacent of said lugs.

7. Load transfer apparatus comprising a longitudinal joint foundation member of which a longitudinal marginal section is adapted for disposition beneath the edge of a paving slab or the like, a plurality of cut-away sections in said marginal section, slab anchorage lugs anchored within and projecting upwardly through said cut-away sections for movement transversely of said member, and a strip of crushable material L-shaped in transverse section, one leg of said strip being disposed flatly upon said marginal section and containing perforations through which said lugs project, and the other leg of said strip projecting a distance substantially co-extensive with the thickness of said marginal section and being disposed along the free edge thereof.

8. Load transfer apparatus comprising a longitudinal joint foundation member having a plurality of cut-away sections spaced apart lengthwise thereof, slab anchorage means disposed in said cut-away sections for movement with a slab transversely of said member, and means for initially holding said anchorage means in predetermined relation with said sections and for excluding foreign material therefrom, comprising crushable means disposed between said anchorage means and said member at said sections.

9. The combination set forth in claim 8 and wherein there is a bar-like member extending lengthwise of the foundation member and rigidly connected with said anchorage means for such transverse movement therewith and operable to transmit a force applied to any one of said anchorage means to adjacent of said anchorage means, whereby such force will be opposed by the crushable material about said adjacent anchorage means as well as by that about the one of said means.

ALBERT C. FISCHER.
